COMBINED DISPLAY AND MERCHANDISING STAND FOR WATER SKIS AND ACCESSORIES OR THE LIKE

Daniel W. Burch, Jr., Louisville, Ky., assignor to Puritan Cordage Mills, Louisville, Ky., a corporation of Kentucky

Filed June 9, 1960, Ser. No. 60,897

Term of patent 7 years

(Cl. D80—10)

Fig. 1.

Fig. 2.

Fig. 3.

FIG. 1 is a front perspective view of a combined display and merchandising stand for water skis and accessories or the like, showing my new design.

FIG. 2 is a right side elevational view thereof.

FIG. 3 is a rear perspective view thereof, it being understood that the apertures shown fragmentarily in the top front panel are continuous throughout said panel.

I claim:

The ornamental design for a combined display and merchandising stand for water skis and accessories or the like, as shown.
